Primary Examiner — Eric L Goodman*Assistant Examiner* — Sanjeev Paul(74) *Attorney, Agent, or Firm* — Middleton Reutlinger**(57) CLAIM**

The ornamental design for a mattress cover, as shown and described.

DESCRIPTION

FIG. 1 is a front elevational view of the mattress cover of the present invention;
FIG. 2 is a rear elevational view of the mattress cover of FIG. 1;
FIG. 3 is a left side elevational view of the mattress cover of FIG. 1;
FIG. 4 is a right side elevational view of the mattress cover of FIG. 1;
FIG. 5 is a top view of the mattress cover of FIG. 1;
FIG. 6 is a bottom view of the mattress cover of FIG. 1; and,
FIG. 7 is a perspective view of the mattress cover of FIG. 1. The broken lines shown in the drawings are included for the purpose of illustrating unclaimed portions of the mattress cover and form no part of the claimed design.
